UNITED STATES PATENT OFFICE.

LOUIS PHILIPPE, OF NEW YORK, N. Y.

DESIGN FOR A PERFUME BOTTLE.

Application filed August 31, 1923. Serial No. 7,130. Term of patent 3½ years.

To all whom it may concern:

Be it known that LOUIS PHILIPPE, a citizen of the United States, residing at No. 318 West 23rd Street, of the city and county of New York and State of New York, has invented a new, original, and ornamental Design for a Perfume Bottle, of which the following is a specification, reference being had to the accompanying drawings, forming part thereof.

I claim:

The ornamental design for a perfume bottle as shown.

In testimony whereof, I have hereunto affixed my hand this 23rd day of August, 1923.

LOUIS PHILIPPE.
